HUMIDIFYING-RADIATOR.

1,203,075.

Specification of Letters Patent.

Patented Oct. 31, 1916.

Application filed February 25, 1915. Serial No. 10,424.

To all whom it may concern:

Be it known that I, ALBERT W. THOMPSON, a citizen of the United States, and resident of Fitchburg, county of Worcester, 5 State of Massachusetts, have invented an Improvement in Humidifying-Radiators, of which the following description, in connection with the accompanying drawing, is a specification, like characters on the drawing 10 representing like parts.

This invention relates to improvements in radiators and the object thereof is to provide a radiator of the usual type employed for heating living rooms with chambers 15 adapted to contain water or other desirable vaporizable fluid so disposed in relation to the heating conduits of the radiator that a sufficient amount of water will be evaporated to maintain the room at a desired degree 20 of humidity without danger of overcharging the atmosphere with moisture and without liability of injuring the walls, furniture, etc., by the vapor.

I am aware that heretofore various kinds of 25 receptacles have been employed in connection with radiators to provide for the humidification of the room but in most instances these devices comprise relatively small tanks and so associated with the radiator construction that when the radiator is highly heated by steam or hot water the 30 contents of the water receptacle is raised to a boiling temperature causing a too rapid vaporization of water with ill effects upon the walls of the room and the furniture and also so overcharging the atmosphere of the room 35 with vapor as to make it oppressive to people within the room.

I am also aware that radiators have been 40 heretofore made with an evaporating section separate and distinct from the heating section but in such constructions the vaporizing sections are frequently made operative while the heating sections are still cold consequently supplying an excess of vapor to 45 the atmosphere so that it is likely to condense upon the walls, furniture and other objects within the room.

By my improved radiator construction 50 the aforesaid objectionable features are avoided and means provided whereby the moisture supplied to the room will vary in the proper proportion to the heating of the atmosphere.

In my construction each radiator unit is 55 provided with a humidifying chamber so disposed in relation to the heating conduits as to be within the lateral planes thereof, thus providing means whereby any number of such units may be assembled to form the 60 complete radiator according to the requirements of the room, furthermore such a radiator has the same appearance as the usual radiators used in steam heating systems and is equally accessible for cleaning. In my 65 preferred construction I have also provided means whereby the water chambers of the radiator may be readily exposed for the purpose of filling the water chamber or for cleaning the same. 70

The drawings illustrate the preferred embodiments of the invention.

Figure 1 shows a radiator embodying my invention standing on the floor of the room and connected with means outside of the room 75 for maintaining a constant supply of water in the evaporating chambers of the radiator, Fig. 2 is a vertical sectional view of one of the radiator units of the preferred construction, Fig. 3 is a horizontal sectional view 80 on lines 3—3 Fig. 2, Fig. 4 is a vertical sectional view of a modified form of radiator construction, and Fig. 5 is a horizontal surface view on lines 5—5, Fig. 4.

The radiator as illustrated in Figs. 1 and 85 2 of the accompanying drawings comprises a series of units or sections 1, each section comprising parallel vertical conduits 2 for a heating fluid such as steam or hot water, said conduits being connected at the bottom 90 by a relatively large chamber 3 thus forming a U-shaped conduit. The several units are connected at the bottom preferably by push nipples 5 and at the top by push nipples 6 thus providing for a constant circulation 95 of fluid through the series of radiator sections. The heating fluid, if steam, may be introduced at the bottom of the radiator through the pipe 4 in the usual manner passing thence through the conduits 2 and the 100 push nipples 5 and 6. When hot water is used the same may be introduced through the pipe 4 at the top of the radiator, passing thence through the push nipples 6, the conduits 2 and chamber 3, leaving through 105 the usual discharge opening in the manner usual in hot water systems.

Each section is provided with a water

chamber 7 within the loop formed by the vertical conduits 2 and the horizontal connecting chamber 3, the sides of the water chamber 4 being flush with or within the lateral planes of the walls of the conduits 2. The walls of the conduits 2 and of the water chamber 7 are desirably made integral being connected by relatively thin webs 8 of such cross section as to reduce the heat conducted from the heating conduits to the water chamber sufficiently to maintain the water in the chamber at a desired vaporizing temperature below the boiling point of water. In some instances, especially where steam is used the heat conducting area of the webs may be still further reduced by cutting away the webs at intervals to form slots 9 in which the air may circulate. By this means any radiator of my construction may be adapted for the particular room in which it is to be located so that it will supply the amount of moisture necessary to maintain the room at the desired degree of humidity.

25 The water chambers of the radiator sections constructed in the manner aforesaid are connected by push nipples 10 so that all of the water chambers of each radiator are connected together and a uniform level of water maintained throughout the entire radiator.

It is sometimes desirable where a large number of radiators are used upon a single floor to provide means for maintaining the water in the water chambers at a constant level, such means may be easily provided by the means illustrated in Fig. 1 which consists in a float tank 11 located in an adjacent room or closet connected by a suitable pipe 12 with an inlet pipe 13 leading to the first section of the water chamber of the radiator. This pipe may be concealed beneath the floor of the room and provided with a riser lying adjacent to the riser of the steam pipe which leads to the steam conducting sections of the radiator.

In the preferred embodiment illustrated in Fig. 2 the heating conduits are U-shaped, the upper end of each leg of the conduit being connected through the nipple 6 of the adjacent radiator section. This leaves the upper ends of the water chambers open so that the same are accessible for cleaning by a brush or cloth. A suitable perforated cover 14 of the required width and length may be provided to inclose the top of the radiator thus constructed.

In order to make the radiator construction more hygienic the walls of the water chamber 7 may be provided with a coating 15 of porcelain, enamel or like substance.

In Fig. 4 I have illustrated a modified form of radiator which is substantially identical in form with the usual radiator now in use. In this construction the radiator sec-

tions are composed of parallel vertical conduits 21 for heating fluid, connected at the bottom by a chamber 23 and at their top by an arch shaped conduit 24. The water chamber 25 is, as disclosed in Fig. 4, disposed within the lateral planes of the walls of the heating conduits and is provided at its top with a relatively large opening 26 adapted to permit the free evaporation of the water within the water chamber. The lower portion or bottom of the water chamber may be made distinct from and separated from the outer wall of the chamber 23 to provide an air space 27 beneath the lower end of the water tank. The walls of the water tank 30 and of the conduit are preferably cast integral, the webs connecting the same being relatively thin and cut away to provide apertures or slots 28 by means of which the radiating area of the web may be sufficiently reduced to maintain the water at the desired temperature. In this construction the several sections of the radiator are connected at the bottom by push nipples entering apertures 29 at the bottom and similar push nipples entering apertures 30 at the top as in the usual radiator construction. It is especially desirable to use means for maintaining a continuous supply of water to the water chambers of radiators of this type since the water chambers are not so easily accessible as the type disclosed in Fig. 2 and it is to be understood that such radiators may be connected to the float tank in the manner heretofore described.

With the radiator construction disclosed herein a relatively large body of water is maintained within the radiator sections and the heat transferred to the water chambers is proportional in each case to the amount of heat delivered to the room. By properly reducing the area of the webs connecting the water chambers with the walls of the steam conduits a nice adjustment may be made which will cause approximately the desired amount of moisture to be supplied to the air at all times.

While I have described the water chamber of the radiator as being constructed preferably integral with the walls of the conduit it is to be understood that the water chamber may be made separate from the conduit and assembled within the same, the walls of the conduit and of the water chamber being connected by a web of suitable conducting material.

It will be understood that the embodiment of the invention disclosed herein is illustrative merely and that it may be embodied in other forms within the spirit and scope of the following claims.

Having thus described my invention what I claim as new and desire to secure by Letters Patent is:

1. A radiator unit comprising a conduit

- for a heating fluid and an open chamber adapted to contain a vaporizable fluid, the wall of said chamber being connected to the wall of the conduit by a relatively thin web 5 of heat conducting material apertured to reduce the conducting area of said web sufficiently to maintain the contents of said chamber at a desired temperature below the boiling temperature of the liquid.
- 10 2. A radiator unit comprising parallel connected conduits for a heating fluid, an open water chamber intermediate of said conduits extending substantially to the top thereof the walls of said conduit and said 15 chamber being connected by relatively thin webs of heat conducting material, the external surfaces of which are exposed to the atmosphere whereby the radiation of heat therefrom is adapted to reduce the amount 20 of heat which otherwise would be transmitted to the contents of said water chamber.
3. A radiator unit comprising integral parallel substantially cylindrical conductors 25 for a heating fluid, an open water chamber intermediate of said conductors and within the lateral planes thereof, the walls of said conduit and said chamber being connected by relatively thin webs integral both with 30 the walls of the conduits and of the chamber and having their external surfaces exposed to the atmosphere whereby the radiation of heat therefrom is adapted to reduce the amount of heat which otherwise would be 35 transmitted to the contents of said water chamber.
4. A radiator comprising a series of connected units each having parallel substantially cylindrical conduits for a heating fluid, 40 an open water chamber intermediate of the conduits of one of said units and within the lateral planes thereof, the walls of said chamber being connected to the walls of the inclosing conduit by thin integral webs having 45 their external surfaces exposed to the atmosphere whereby the radiation of heat therefrom is adapted to reduce the amount of heat which otherwise would be trans-

mitted to the contents of said water chamber.

50

5. A radiator comprising a series of connected units each having vertical parallel conduits for a heating fluid, a water chamber open at its top intermediate of said conduits and within the lateral planes thereof, 55 relatively thin webs having their external surfaces exposed to the atmosphere connecting the walls of the conduits to those of the water chamber and means connecting said water chambers whereby a uniform level of 60 water will be maintained throughout the series of water chambers.

55

6. A radiator comprising a series of connected units each having vertical parallel conduits for a heating fluid, a water chamber open at its top intermediate of said conduits and within the lateral planes thereof, webs connecting the walls of the conduits to those of the water chamber throughout a portion of their adjacent surfaces, the walls 70 of the water chamber and of the conduits being separated throughout the remainder of their adjacent portions to provide apertures for the circulation of air, whereby the desired temperature of the water in the receptacle may be maintained.

75

7. A radiator comprising a series of connected units each having vertical parallel conduits for a heating fluid, connecting water chambers open at their tops intermediate of the conduits of each unit and within the lateral planes thereof, webs having their external surfaces exposed to the atmosphere connecting the walls of the conduits to those of the inclosed water chambers, a cover plate removably secured to the top of said radiator units and water supplying means adapted to maintain the water chambers practically full at all times.

80

In testimony whereof, I have signed my 85 name to this specification, in the presence of two subscribing witnesses.
